POLE GRIPPER FOR LADDERS

Roy H. Risser, West Hazleton, Pa., assignor to
 H. F. Husted Company, Hazleton, Pa., a partnership composed of A. Ernest Shafer and Roy H. Risser

Application April 26, 1933, Serial No. 668,126

4 Claims. (Cl. 228—61)

This invention relates generally to ladders and particularly to means associated with a ladder structure whereby to stabilize the ladder when applied to telephone or electric light poles, trees 5 or in fact any surface of relatively small diameter against which it has heretofore been found difficult to properly stabilize or support the ordinary rung ladder.

A further object of the invention is to provide 10 an attachment for application to the ordinary ladder having parallel or near parallel side bars to adapt the same for application to poles or posts, thus obviating the necessity of ladders especially constructed for such uses.

15 A further object of the invention is to provide a ladder attachment for the purposes set forth of such character that the stabilizer automatically adapts or adjusts itself to the pole or post and maintains the upper end of the ladder in 20 proper stabilized position.

A still further object is to provide a device of the character stated which may form a part of the ladder as originally constructed or which may be applied to ladders now in use with little or no 25 difficulty and without the aid of special skill or tools; which may be manufactured at extremely low cost, which is of simple construction, which in no way interferes with the use of the ladder in other environments, which is so constructed 30 and assembled as to obviate the possibility of breakage or derangement, which requires no adjustment or attention after once being applied, and which will prove highly practical and efficient in operation.

35 With these objects in view, together with others which will appear as the description proceeds, the invention consists in the novel construction, combination and arrangement of parts, all as will be described more fully hereinafter, illustrated in the drawing and particularly pointed out in the claims.

In the drawing:—

Fig. 1 is an elevation of the upper end of a conventional ladder having parallel sides and illustrating as applied thereto a ladder or gripper constructed in accordance with the invention, parts being broken away to show the detail construction.

Fig. 2 is an enlarged perspective view of one 50 of the socket members used in attaching the gripper to the ladder, and

Fig. 3 is a similar view showing the gripper member detached from the ladder and with the covering removed.

55 In general, the invention resides in an adapter

or gripper member disposed near the upper end of the ladder, the said gripper being swingingly mounted and so shaped as to conform substantially to a circular or near circular object or support. The gripper member is free to swing or oscillate in order that automatic adaptability of the gripper to the supporting surface may be assured. The gripper member is so balanced as to normally maintain a position such as will bring the same into proper and positive securing 10 engagement with the support when the ladder is leaned against the same with its side members straddling said support. The gripper member is provided with means whereby snug engagement between the gripper and support is assured, in 15 order to prevent slippage after the ladder has once been applied to the object.

Referring now more particularly to the drawing, the conventional ladder is represented as having parallel or substantially parallel side 20 members 2—3, the uppermost rung of the ladder being indicated at 1. The gripper is represented generally at 4, while a covering for the same is indicated at 5. The gripper member per se consists of a metallic bar somewhat less in length 25 than the distance between the side members 2—3, and this bar is bent into such shape as will enable the same to properly and snugly embrace or engage with a tree, pole or post. The gripper bar may take the form of a yoke substantially as shown, being bent intermediate its ends to provide an apex with divergent substantially straight arms projecting therefrom. By so shaping this element, it is at once apparent that the bar will substantially correspond and adapt itself to circular or near circular objects such as poles, posts and trees. The covering 5 may be of rubber, 30 leather, fabric or any other material offering frictional resistance.

It is preferred that the gripper member thus formed be positioned and supported between the ladder sides so as to normally have its apex portion disposed downwardly, in order that the same may automatically adapt itself to a substantially cylindrical surface by merely causing the upper end of the ladder sides to straddle such object. Therefore, the yoke is pivoted or suspended in such manner that the bulk of its weight is disposed below the pivotal supports. This function may be accomplished by having the extremities of the yoke arms pivotally attached to the ladder sides, or pintles 9 may be provided near the ends of the yoke arms. The pintles 9 are preferably formed integral with the bar itself and are disposed in parallel alignment with each other and 40

project outwardly from the said yoke arms slightly inwardly from the extremities thereof. The ends of these pintles are rotatably supported within socket members 10 carried by base plates 6 secured to the inner faces of the ladder sides by having bolts 7 pass through suitable openings 8 in said plates as well as through the ladder sides. By thus mounting the yoke or gripper member it is apparent that the same is free to rotate in a direction parallel to the ladder rungs, whereby to insure automatic adaptability of the gripper member with a pole or post. As the greater part of the gripper bar 4 is disposed below the horizontal plane of the pintles 9, the gripper member will normally assume a position with its apex downward so that the said yoke or gripper member is at all times in proper position for engagement with a support straddled by the ladder sides. By constructing the gripper member in this manner, substantially the entire space between the inner faces of the ladder sides is spanned by the arm portions of the gripper, thus enabling the device to properly rest upon and grip with poles, trees or posts of a wide range of diameters, or practically to any diameter up to the depths between the ladder sides. When the ladder is applied to flat surfaces, such as walls, the gripper will remain in its normal position with apex downward and thus offers no interference to usual ladder operations.

From the foregoing it is obvious that I have provided a pole gripper for ladders of extremely simple construction and which will adequately accomplish the various results for which it is designed. The ordinary rung ladder provided with an attachment of this character obviates the necessity of providing a ladder of special construction heretofore adopted and used in connection with poles and trees, and particularly poles or posts of metal such as are commonly used as electric light and trolley poles.

While the foregoing is a description of the invention in its preferred embodiments, it is never-

theless to be understood that variations in the structural details and manner of assemblage may be resorted to without departing from the invention as defined by the claims.

Having thus described my invention, I claim:— 5

1. In a ladder structure, a gripper interposed between the sides of the ladder and comprising a rigid support engaging yoke, aligned pintles extending laterally from the yoke and pivotally secured to the side members of the ladder, the yoke being constructed and arranged to move about its pivots to straddle the ladder support thereby securing the ladder against lateral movement relative to the support. 10

2. In a ladder structure, a gripper interposed between the sides of the ladder and comprising a rigid V-shaped ladder support engaging yoke, aligned pintles extending laterally from the yoke and pivotally secured to the side members of the ladder, the yoke being constructed and arranged to move about its pivots to straddle the ladder support thereby securing the ladder against lateral movement relative to the support. 15

3. In a ladder structure, a rigid one-piece yoke interposed between the sides of the ladder, a 25 socket member secured to each side member of the ladder, aligned pintles extending from the yoke and pivotally supported by the sockets to permit the yoke to move about its pivots and straddle the ladder support thereby securing the 30 ladder against lateral movement relative to its support.

4. In a ladder structure, a rigid one-piece bar bent longitudinally intermediate its ends into substantially V-shape, the distance between the ends 35 of said bar being slightly less than the distance between the ladder sides, pintles integral with and projecting outwardly from said bar near the ends of the latter, the said pintles aligned with each other, and sockets on said ladder sides to 40 rotatably support said pintles.

ROY H. RISSE.
